UNITED STATES PATENT OFFICE.

HENRY WITTEKIND, OF CHICAGO, ILLINOIS.

METAL SHEET-PILING.

SPECIFICATION forming part of Letters Patent No. 794,268, dated July 11, 1905.

Application filed November 17, 1904. Serial No. 233,068.

To all whom it may concern:

Be it known that I, HENRY WITTEKIND, a citizen of the United States, residing at Chicago, county of Cook, State of Illinois, have 5 invented a certain new and useful Improvement in Metal Sheet-Piling; and I declare the following to be a full, clear, and exact description of the invention, such as will enable others skilled in the art to which it pertains to 10 make and use the same, reference being had to the accompanying drawings, which form a part of this specification.

My invention relates in general to piling for use in constructing caissons, coffer-dams, 15 foundations for buildings, bridges, &c., and more particularly to metal sheet-piling.

The primary object of my invention is to provide a metal sheet-piling consisting in a series of duplicate sections composed of stand- 20 ard rolled beams, the sections adapted to be interlocked as they are successively driven.

A further object of my invention is to provide a metal sheet-piling composed of duplicate sections which may be readily interlocked as they are successively driven, so as 25 to render the piling strong and waterproof, and which at the same time will be simple in construction and durable in use.

The embodiment of my invention herein disclosed may be generally described as consisting in a metal sheet-piling composed of 30 duplicate interlocked sections, each section comprising a vertical central plate, a Z-beam, one side flange of which overlaps and is rigidly secured to one side of the plate, while the other flange of the Z-beam extends outwardly in a plane parallel to the central plate, an angle-beam secured to and extending around the other side edge of the central plate, 35 and means for spacing the angle-beam from the plate to form therewith an angular channel conforming in cross-section to the cross-section of the projecting portion of the Z-beam.

My invention will be more fully described hereinafter with reference to the accompanying drawings, in which the same is illustrated as embodied in a convenient and practical form, and in which—

50 Figure 1 is an elevational view of two in-

terlocked sections; and Fig. 2, a sectional view on line 22, Fig. 1.

The same reference characters are used to designate the same parts in the two figures of the drawings.

Reference character A indicates a vertical plate of any desired height, width, and thickness, suitable for use in constructing metal sheet-piling.

C indicates an angle-beam extending around 60 one side edge of the plate A and spaced apart therefrom to form an angular channel c.

Any suitable means may be provided for spacing the angle-beam C from the edge of the central plate A—such, for instance, as a 65 strip D interposed between the plate and the edge of the angle-beam. Any suitable fastening device may be provided for rigidly uniting the angle-beam to the plate A—such, for instance, as rivets d fastened through registering openings in the plate, filler-strip, and angle-beam.

In lieu of employing the filler-strip D the channel between the angle-beam C and plate A may be formed by offsetting vertically the 75 inner edge of the angle-beam, as clearly shown and described in my prior United States Patent No. 744,847, dated November 24, 1903.

A Z-beam B is rigidly secured to the side edge of the plate A opposite to the edge around 80 which the angle-beam C extends. One flange b' of the Z-beam B overlaps the side edge of the central plate A and is rigidly secured thereto by any suitable means—such, for instance, as rivets d. The flange b' of the Z-beam is preferably located on the opposite face of the central plate to that on which is secured the angle-beam C. The other flange b of the Z-beam projects outwardly from and in a plane 85 parallel to the central plate A, as clearly 90 shown in Fig. 2.

In constructing a sheet-piling by the use of my improved duplicate vertical sections the several sections are successively driven, the projecting portion of the Z-beam of one section 95 being interlocked with the angular channel of the previously-driven section. It is obvious that the section to be driven may be equally as well engaged with the previously-driven section by engaging the channel therein with 100

the projecting portion of the **Z**-beam, it being evident that each section occupies an inverted position with respect to the previously-driven section. A piling of any desired length may 5 be readily constructed by driving the desired number of duplicate sections.

From the foregoing description it will be observed that I have invented an improved metal sheet-piling composed of duplicate sections, each section having at one side an angular channel of a cross-section to correspond to an angular beam projecting from the other side thereof. It will be further observed that a piling constructed of my improved duplicate 10 sections will constitute a rigid wall, the parts of which are securely held against lateral as well as longitudinal separation, the longitudinal separation being prevented by the flange *c* of the angle-beam and the lateral separation 15 being prevented by the flange *b* of the **Z**-beam *B* through its interlocked engagement with the angular channel formed between the central plate and the angle-beam *C*.

While I have described more or less precisely the details of construction, I do not wish to be understood as limiting myself thereto, as I contemplate changes in form, the proportion of parts, and the substitution of equivalents, as circumstances may suggest or render 20 expedient, without departing from the spirit of my invention.

Having now fully described my invention, what I claim as new, and desire to secure by Letters Patent, is—

35 1. A metal sheet-piling composed of inter-

locked duplicate sections, each section having an offset laterally-projecting flange at one side edge and an angular channel at its other side edge of a cross-section to receive the flange on the adjacent section. 40

2. In a metal sheet-piling; a section composed of a plate, an offset laterally-projecting flange at one side edge, and an angular channel at its other side edge conforming in cross-section to said flange. 45

3. In a section for metal sheet-piling, the combination with a central plate, of a **Z**-beam having one flange rigidly secured to one side of said plate and its other flange projecting laterally, an angle-beam spaced apart from 50 said plate and extending around the other side of said plate thereby forming a channel conforming in cross-section to the projecting portion of said **Z**-beam.

4. In a section for metal sheet-piling, the combination with a central plate, of a **Z**-beam having one flange rigidly secured to one side of said plate and its other flange projecting laterally therefrom, an angle-beam extending around the other side edge of said plate, and 55 a filler-strip interposed between said plate and angle-beam thereby forming a channel corresponding in cross-section to a portion of said **Z**-beam projecting from said plate.

In testimony whereof I sign this specification 60 in the presence of two witnesses.

HENRY WITTEKIND.
